UNITED STATES PATENT OFFICE.

SALLIE C. TUCKER, OF GARNETT, KANSAS.

BUCKLE.

SPECIFICATION forming part of Letters Patent No. 400,018, dated March 19, 1889.

Application filed February 17, 1888. Serial No. 264,345. (No model.)

To all whom it may concern:

Be it known that I, SALLIE C. TUCKER, of Garnett, in the county of Anderson and State of Kansas, have invented a new and Improved 5 Buckle for Tailor's Measuring and Fitting Apparatus, of which the following is a full, clear, and exact description, reference being had to the accompanying drawings, in which—

Figure 1 is a perspective of my improved buckle, and Fig. 2 shows the same in connection with crossing measuring-tapes.

The invention will first be described, and then specifically pointed out in the claims.

The buckle consists of two parallel end 15 loops, 40 40, connected at their lower outer corners by a cross-bar, 42, and also connected above said cross-bar by a horizontal loop, 44, the upper and lower bars of which are in vertical alignment. Thus the two tape or strap 20 passages cross each other at right angles. To the lower cross-bar, 42, a $\square$ -shape tongue, 43, is pivoted, its upper serrated cross-bar striking against the outside of the lower bar of the loop 44.

25 41 is a penetrating-point projecting inwardly across the horizontal passage through the left-hand loop, 40, from the outer bar thereof, this penetrating-point being shown as a continuation of the lower bar of the 30 loop 44, one measuring-strap passing through the passage formed by the vertical loops 40, and the crossing tape or strap passing through the loop 44, over the serrated edge of the loop 43, and then down in rear of the cross-bar 42.

35 Either tape or strap may be readily adjusted and fastened without interfering with the adjustment of the one crossing it. The buckle may be slid horizontally to the right on the tape; but a reverse movement will cause the

penetrating-point to enter the tape or strap 40 and hold the buckle.

Having thus described my invention, what I claim, and desire to secure by Letters Patent, is—

1. The combination, with a buckle having 45 passages crossing each other at right angles, an inclined penetrating-point projecting across one passage from the outer wall thereof, and a pivoted tongue for the other passage having a serrated cross-bar at its free end, of 50 the two crossing measuring-tapes passing through said passages, one tape being engaged by the penetrating-point and the other by the serrated cross-bar, substantially as set forth. 55

2. The herein-described buckle, comprising two parallel end loops, one of which loops has an inwardly-projecting penetrating-point, the horizontal connecting-loop connecting the end loops, the cross-bar connecting said end loops 60 below the horizontal loop, and the tongue pivoted on the said cross-bar and extending up to the horizontal loop, substantially as set forth. 65

3. The herein-described buckle, consisting in the vertical end loops, 40 40, the cross-bar 65 42, connecting the outer sides of said loops at or near their lower ends, the horizontal loop 44, connecting the outer sides of the loops above said cross-bar and having one of its bars extended to form the penetrating-point 70 41, and the $\square$ shape tongue 43, pivoted on cross-bar 42, extending up to said loop 44, substantially as set forth. 75

SALLIE C. TUCKER.
